CLAIM

(**) Term: **14 Years**

The ornamental design for a spotlight with rechargeable quartz halogen, as shown and described.

DESCRIPTION

FIG. 1 is a perspective view from the front-top-right side of the spotlight with rechargeable quartz halogen showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1; and,

FIG. 8 is a front top right perspective view of the design showing the lamp on a pivoted position relative to the base.
